UNITED STATES PATENT OFFICE.

CHARLES S. SPITZER AND JOHN GLOUB, OF CHICAGO, ILLINOIS.

PHONOGRAPH.

Application filed May 7, 1921. Serial No. 467,755.

To all whom it may concern:

Be it known that we, CHARLES S. SPITZER and JOHN GLOUB, both citizens of the United States, and residents of Chicago, in the county of Cook and State of Illinois, have invented certain new and useful Improvements in Phonographs, of which the following is a full, clear, and exact description.

The invention relates to phonographs. 10 One object of the invention is to provide an improved phonograph in which the amplifier is enclosed and constructed so that the sound will be deflected through its enclosure in substantially all directions, this object being attained by providing an amplifier. Another object of the invention is to provide an improved amplifier and an improved tone-arm. Other objects of the invention will appear from the description. 15 20 The invention consists in the several novel features hereinafter set forth and more particularly defined by a claim at the conclusion hereof.

In the drawings: Fig. 1 is a front elevation of a phonograph. Fig. 2 is a side elevation, the cover containing the amplifier being shown in its raised position. Fig. 3 is a vertical longitudinal section. Fig. 4 is a side elevation of the amplifier, the cabinet and cover being shown in section. Fig. 5 is a horizontal section taken on line 5-5 of Fig. 2. Fig. 6 is a detail section of the tone-arm.

The invention is exemplified in a cabinet 35 6 which may be of any suitable construction, the one illustrated corresponding to the structure included in Letters Patent No. 1,402,383 granted to us January 3, 1922. This cabinet is provided with a top 7 which 40 comprises a removable central section 8 on the underside of which a motor 9 of any suitable construction is mounted. An enclosing case 10 for said motor is also secured to the underside of top-section 8. A 45 record-holder or table 11 connected to be driven by the motor is rotatable above the cabinet top 7, in manner well understood in the art. A reproducer 12 is suitably connected to the outer end of a tone-arm 13 which is made of natural cows' horn. This 50 material has been found to form an efficient conductor for sound which will avoid metallic strains in the reproduction of a record. The horn is secured to a ring 13' on the case 55 of the reproducer by a screw-thread 13" and is connected by a hinge 14 and telescopically,

as at 15, to an elbow 16 which is rotatably mounted on a post 17 which is fixed to the top-section 8. A set-screw, having a terminal extending into a groove 19 in post 17, holds the elbow 16 on the post so it will be free to rotate with the tone-arm and so that it may be removed from the post when desired.

A cover is movably mounted on top of the cabinet and comprises a base-frame 20, sides 21, all of which have openings therein for the escape of sound, and a top comprising a sloping portion 22 and a flat portion 23. This top serves as a hood or container for an amplifier 24 for the sound from the tone-arm and is vertically movable so as to provide access to the top of the cabinet, so that records may be placed on and removed from the record-holder 11. The cover is fixed to a pair of vertical rods 25 which are slidably mounted in vertical sockets 26 formed in the corners of the cabinet 6. Springs 27 in the lower ends of the sockets act on said rods to press the cover normally upward 80 and away from the cabinet-top. A stud 28 is adapted to extend through a hole 30 in the top 7 of the cabinet and is provided with a notch 29 which is adapted to receive a latch-lever 31, which is pivoted to the cabinet, at 32, and normally pressed into operative position by a spring 33. The lower end of stud 28 is pointed so as to pass the latch-lever and so that the lever will automatically snap into notch 29 when the cover 90 is lowered. When the latch-lever is released, the springs 27 will automatically lift the cover and the parts carried thereby.

The improved amplifier 24 is preferably formed of a natural sea-shell and is secured to the section 23 of the cover by screws 34. This amplifier is provided with an inlet opening, at 35, and a helicoidal conduit 36 of progressively increasing size and which terminates into a large open-ended outlet 100 portion 37 which faces downwardly. A flared head and deflector 38' is formed of vellum stretched over ribs on and spaced from a correspondingly flared or pyramidal bottom 38 for the cover which is secured on the base-frame 20. The head 38' is spaced from the outlet of the amplifier and acts as a drum-head to amplify the sound as well as a deflector for the sound issuing from the amplifier 24. A characteristic of this construction is that the downwardly discharged sound will be deflected in substantially all 110

directions from the outlet of the amplifier and through all of the sides 21 of the cover. In practice, it has been found that the helicoidal conduit in a sea-shell will efficiently conduct and amplify the sound.

A metal tube 39 is fixedly supported in the cover and has its upper end suitably secured to the inlet 35 of the amplifier. The sound connection between the tube 39 and elbow 16 10 comprises a pair of telescopic sections 40 and 41. Section 40 is adapted to slide into the elbow 16, being provided with a flange 42 which is adapted to engage a ring 43 on the elbow to limit the upward movement of section 40. Sections 41 and 40 are provided with overlapping flanges 44 to retain them in connected relation. Section 41 is adapted to slide into the lower portion of the tube 39. A removable ring 45 is adapted to engage a flange 46 on the upper end of section 41 to prevent disconnection of tube 39 and section 41 when opening and closing the cover.

When the cover is in the position shown in Figs. 2 and 3, the record-holder 11 will be accessible so that a record disk may be placed thereon or removed therefrom when the tone-arm 13 is lifted. When the reproducer and record have been put into operative relation, the cover may be lowered into closed position, as shown in Figs. 1 and 4. In lowering the cover, the tubular sections between elbow 16 and tube 39 will telescope into one another as shown in Fig. 4. During the operation of the record-holder, the tone-arm will rotate with elbow 16 on post 17 and the sound will pass through the tone-arm 13, elbow 16, tubular sections 40, 41 and tube 39 to the inlet 35 of the amplifier. The sound connection between the tube 39 and elbow 16 remains complete when the cover is raised, so that the sound will be conducted

to the amplifier when the cover is raised, as well as when it is lowered. The sound passing into the inlet 35 continues through the helicoidal conduit 36 to the enlarged outlet 37, from which it passes downwardly and laterally in substantially all directions, being deflected by the deflector 38 through the openings in the cover-sides 21 which are usually lined with a textile fabric 48, as well understood in the art.

The invention exemplifies a phonograph in which the amplifier is enclosed in, and movable with, the cover of the cabinet; in which the sound from the amplifier is deflected laterally in substantially all directions after leaving the amplifier; in which the cover, containing the amplifier, is vertically slidable to provide access to the record holder with a telescopic connection with the tone-arm, so that the instrument will be operative when the cover is raised, as well as when it is lowered; in which the amplifier is provided with a helicoidal conduit and formed of sea-shell.

The invention is not to be understood as restricted to the details set forth, since these may be modified within the scope of the appended claim, without departing from the spirit and scope of the invention.

Having thus described the invention, what we claim as new and desire to secure by Letters Patent, is:

In a phonograph cabinet, a tone arm, a vertically slidable hollow cover over the cabinet, an amplifier disposed in the cover, a sound-connection between the amplifier and the tone arm, and means for automatically lifting the cover comprising rods for guiding said cover vertically, and springs at the ends of said rods for lifting said cover.

CHARLES S. SPITZER
JOHN GLOUB.
